TOY

Frank H. Pierce, New York, N. Y., assignor of
seventy per cent to Samuel E. Witt, New York,
N. Y.

Application August 11, 1937, Serial No. 158,459

2 Claims. (Cl. 46—191)

This invention relates to improvements in toys and more particularly toys in which a bat or a paddle and a return ball attached thereto is used.

5 An object of the invention is to provide an improved toy having a bat and return ball attached thereto in which a snapping noise or signal will be given when the ball is properly struck or in which a signal is heard when the ball leaves the bat or paddle.

10 A further object of the invention is to provide an improved bat having ornamental features not hitherto employed in bats of this character.

15 Further objects of this invention will be apparent from the specification and drawing in which:—

Fig. 1 is a top plan view of the toy, with the striking disk member partially broken away.

20 Fig. 2 is a sectional view on the line 2—2 of Fig. 1.

Fig. 3 is a bottom plan view, with the striking disk member partially broken away.

25 Fig. 4 is a top plan view of another embodiment of the invention with the striking disk member partially broken away.

Figures 5 and 6 are sectional views on the line 5, 6—5, 6 of Fig. 4.

30 Referring to Fig. 1, this shows a bat or paddle having an upper or striking portion 1 and a lower or handle portion 1a. The bat or paddle can be made of any suitable material, such as wood, fibre board or the like.

As shown in Figs. 1 and 2, the front face of 35 the bat is provided with a recess 2a at the central part of the upper portion 1 of said bat.

Said recess 2a is adapted to receive a striking disk member 2, stamped out of any metal or other material adapted to give a signal when 40 struck by a ball. Said disk 2 is stamped or otherwise treated to form a convex springy surface as clearly shown in Fig. 2 and the role this convex disk 2 plays in giving a signal will be hereinafter explained.

45 As shown in Fig. 2, said disk member 2 is provided with a peripheral wall adapted to fit into the recess 2a. Preferably, the disk member 2 is retained in the recess 2a by pins 5 as indicated in Fig. 1. The use of pins or the like may 50 be obviated when the construction of the disk member 2 is such that when it is snapped into the recess 2a its peripheral wall will abut the vertical walls of the recess 2a and the disk will be held securely in position by a frictional or 55 force fit between its peripheral wall and the ver-

tical walls of said recess 2a. It will be noted that the face of the disk member 2 is substantially flush with the playing wall of the paddle.

As shown in Figs. 2 and 3, the rear part of the upper portion 1 of the bat is provided with an opening 4 which is countersunk at 4a. Said opening 4 is located opposite the recess 2a and communicates therewith. The opening 4 is countersunk so as to retain a leaf spring 3. Said spring 3 serves to maintain the disk member 2 in convex or bulged out form. Furthermore said spring 3 is adapted to yield in cooperation with the disk member when the latter is struck by a ball.

The reference numeral 7 indicates a rubber 15 ball having an elastic or rubber string 6, one end of which is secured to the ball 7 and the opposite end to the bat or paddle by a tack 8 as shown in Figs. 1 and 2.

20 A snapping noise, signal or a series of signals may be given or noises may be emitted as follows:

The player grips the handle portion 1a of the bat or paddle and imparts a swinging movement thereto. The elastic string 6 will stretch 25 and said string being attached to the bat, the ball 7 will perform return to said paddle and if controlled accurately will strike the disk member 2 causing the same to yield together with the spring 3 and said disk and spring will assume a 30 slightly concave position as shown by the dotted lines in Fig. 2.

This will produce a signal or noise. The disk member 2 and the spring 3 will then immediately 35 spring back into their original convex out position thus causing a second signal to be given. That is, a double signal is produced and this may be repeated indefinitely if the player accurately aims and controls the return ball.

It is obvious that my improved toy paddle 40 serves the useful purpose of an accuracy testing device in the nature of a noise producing target. That is, if the disc member 2 is properly struck, at substantially its central portion, a noise will 45 be emitted, thus informing the player that he has scored a hit. In this way the player's skill may be readily tested.

Figure 4 shows another embodiment of the invention and provides certain ornamental features. 50 The bat or paddle 1 is provided with a recess at its upper or striking portion. Said recess is adapted to receive a convex disk member 9. Said disk member 9 is provided with a peripheral flange and is securely held in said recess by a 55

frictional or force fit between the peripheral flange and the vertical walls of the recess.

An elastic or rubber string 6 is secured to one end to a ball 7 and at its opposite end to the 5 disk member 9 by a knot 12 through an opening in the center of the disk. When the player causes the ball to strike the disk 9 as shown in Fig. 5, the disk member 9 is forced inwardly thus producing a signal. When the ball leaves the disk 10 and the elastic 6 stretches outwardly, an outward pressure is exerted on said disk member and it then assumes the convex position shown in Fig. 6, thus producing a signal. These signals are independent of each other.

15 Fig. 4 shows two openings 11 having varying colored windows 10. These windows may be peered through by the user and the bat or paddle now serves as a mask or the like giving the user an additional toy.

20 While I have shown the disk member 2, the recess 3a and the opening 4 as circular, I do not wish to be limited in this respect. They may be square or of any desired shape. Likewise, they may be of any desired diameter. Nor do I wish 25 to be limited to any particular form, style or shape of paddle or bat.

I have shown preferred embodiments of my invention, but it is clear that numerous changes and omissions can be made without departing from its spirit.

I claim:

1. A toy or the like comprising a paddle having a recess in one side thereof, a disk member located in said recess, a return ball attached to said paddle, said disk member being flexible and having a normally convex face, said face being 10 adapted to assume a concave position and to produce a snapping noise when struck by said ball and being adapted to return to its normal position when said ball rebounds from said face.

2. A toy or the like comprising a paddle having a recess in one side thereof, a disk member located in said recess, a return ball attached to said disk member, said disk member being flexible and having a normally convex face, said face being adapted to assume a concave position and 15 to produce a snapping noise when struck by said ball and being adapted to return to its normal position when said ball rebounds from said face.

FRANK H. PIERCE. 25
